I claim the ornamental design for a fruit press, as shown and described.

DESCRIPTION

FIG. 1 is a perspective photographic view of a fruit press, showing my new design;

FIG. 2 is a front photographic elevation view thereof;

FIG. 3 is a rear elevation photographic view thereof;

FIG. 4 is a left side elevation photographic view thereof;

FIG. 5 is a right side elevation photographic view thereof;

FIG. 6 is a top plan photographic view thereof; and,

FIG. 7 is a bottom plan photographic view thereof.

The portions enclosed in the broken lines are for illustrative purposes only and form no part of the claimed design.
